US00D559035S

(12) **United States Design Patent** (10) **Patent No.:** **US D559,035 S**
Hayes et al. (45) **Date of Patent:** **** Jan. 8, 2008**

(54) **RIM STRUCTURE FOR CONTAINER**

(75) Inventors: **Thomas J. Hayes**, McHenry, IL (US);
Scott D. Brown, Winthrop Harbor, IL (US); **Neema Pourmohamadian**, Skokie, IL (US)

(73) Assignee: **Pactiv Corporation**, Lake Forest, IL (US)

(**) Term: **14 Years**

(21) Appl. No.: **29/258,354**

(22) Filed: **Apr. 20, 2006**

Related U.S. Application Data

(63) Continuation-in-part of application No. 29/207,825, filed on Jun. 18, 2004, now Pat. No. Des. 525,083, which is a continuation-in-part of application No. 10/277,303, filed on Oct. 22, 2002, now Pat. No. 6,886,704.

(57) **CLAIM**

The ornamental design for rim structure for container, as shown and described.

DESCRIPTION

FIG. 1 is a top perspective view of a rim structure for a container.

FIG. 2 is a top plan view of the rim structure for container of FIG. 1.

FIG. 3 is a side elevational view of the rim structure for the container of FIG. 1, the opposite sides being identical; and, FIG. 4 is a bottom plan view of the rim structure for the container of FIG. 1.

The broken lines in the drawings are for illustrative purposes only and form no part of the claimed design.
